6 Claims. (Cl. 250—36)

The present invention relates to new electron tubes and their utilisation and to circuits employed with such tubes.

This application is a division of our copending application Serial No. 210,332, filed May 27, 1938.

One of the objects of the invention is to improve the output and operation of ultra-high frequency systems, for example, employing frequencies corresponding to wave lengths of the order of the decimeter, the centimeter or even of values considerably lower as well as frequencies of higher wave length.

In order to understand the nature of the present invention, it seems well to make some remarks with regard to the output of the electron tubes employed in particular as oscillators.

The output of the normal oscillator or amplifier tubes, that is to say, those in which the time of transit of the electrons remains short with respect to the period of the oscillation, is all the greater if the alternating tension between electrodes is a fraction higher than the direct tension in the source of supply (the output impedance being assumed to be ohmic).

By applying this reasoning to tubes in which the time of transit of the electrons is comparable to the period, there will be found a double limitation of the output of these tubes. The first is the difficulty in achieving output circuits of a sufficient impedance to obtain these high tensions. This limitation is not directly bound up with the use of electronic oscillators. It is simply due to the high frequencies which it is attempted to use.

The second on the other hand is directly connected with the method of operation of the tubes. One of the conditions necessary for the operation of the present tubes is that the time of transit of the electrons should not depart too much from a mean suitable value related in a fixed manner to the period. Now, this type of transit depends upon the value of the alternating tension superposed on the direct tension. Inasmuch as the high frequency tension is small with respect to the direct tension, the above condition is fulfilled. If it becomes comparable with the direct tension it considerably modifies the time of transit of the electrons which leave at different moments in the period, and thus limits the amplitude of the oscillation. It will consequently be seen that the high frequency tension must always remain small in proportion to the direct tension. In accordance with this reasoning the output of the electron tubes will thus seem theoretically limited to low values.

It is found, however, that the condition offered by normal tubes of only being able to lead to a good output if the alternating high frequency tension becomes comparable with the direct ten-

sion is not inevitable in the case of electronic oscillators. This will be seen by considering not the output but the losses in the tubes and by seeking for the condition which leads to the minimum losses, that is to maximum output.

In the case of tubes in which the time of transit is negligible, the losses are defined at any moment by the product of the tension and of the instantaneous current, or more exactly by the product of instantaneous current multiplied by the speed of the electrons (expressed in volts) arriving at any moment on the positive electrode. Inasmuch as the time of transit of the electrons is negligible the two expressions are equivalent since in this case the speed of the electrons arriving on the positive electrode is equal to the tension of this electrode.

In the case in which the time of transit is comparable with the period the speed of the electrons arriving on an electrode is not always that corresponding to the potential of this electrode. This speed may be higher or lower than the speed corresponding to the tension of this electrode. The difference of speed in proportion to the case of a negligible time of transit may become great, in spite of a low high frequency tension, in the case in which the electrons oscillate several times in the high frequency fields before arriving on the electrode. It will be seen that the instantaneous losses in such a tube are no longer given by the product of the instantaneous current by the instantaneous tension. They may be greater or smaller. This difference is supplied or absorbed by the oscillatory circuit. The output of the tube thus no longer depends in the same way on the high frequency tension on the terminals of the load. The output is increased if the speed of the electrons on arrival on the electrode is smaller than that corresponding to the potential electrode; it is reduced if the speed is increased.

The present invention provides arrangements in which the electrons are systematically slowed down by one or more fields of high frequency, and thus supply energy in one or more oscillatory circuits, losing it themselves.

The present invention in accordance with one of its aspects thus permits the said limitations to be overcome; among others it provides an electron tube particularly adapted to the generation of ultra-high frequency waves, employing one or more electronic bundles associated with such means that the average speed of the electrons of each bundle upon their arrival on a target-electrode is less than the speed which corresponds to the difference of potential between the source of electrons and the target.

In accordance with one feature of the invention these arrangements are such that the re-

tardation of the electrons is produced in the system repeatedly under the action of the same high frequency field, or fields, so as to increase the total energy given by the electrons concerned to the oscillatory circuit.

In accordance with another feature of the arrangement under consideration, the retardation of the mean speed of the electrons is produced by the magnetic or electro-magnetic high frequency field sustained by the energy given up by the slowing down of the average speed of the electrons.

The invention is not limited to the generation of ultra-high frequency waves and the tubes described here may be adapted to be employed 10 for the generation amplification or detection as well as for various other applications, such for example, as in oscillographic systems or television systems, or for measuring apparatus.

The invention will be explained in detail in the 20 case of the generation of ultra-high frequency waves, and indications will be given with regard to its employ in other fields.

The present invention will be better understood by means of the following description based 25 on the attached drawing in which:

Fig. 1 shows a particular embodiment of the invention in which the electronic bundle advances in a zig-zag path; and

Fig. 2 is a section of the guide electrode structure of the device of Fig. 1, along the line 4—4.

Fig. 1 represents another embodiment of a device for the systematic retardation of the electrons comprising an evacuated envelope E in which are arranged an electron gun G, two pairs 35 of deflecting plates D₁, D₂ operating in the ordinary way to produce and define an electron bundle and two pairs of metal retarding plates R₁, R₂ respectively associated with metallic reflecting electrodes P₁ and P₂. Fig. 2 shows a section of this figure along the line 4—4, Fig. 1. The oscillatory output circuit O composed, for example, of a Lecher line is connected to each pair of retarding electrodes, and its middle point is connected to the electron gun G. The reflecting electrodes are connected to a source S₃ of potential negative with respect to the cathode. Targets C₁, C₂ are placed on the two Lecher wires at the end of the structures.

The bundle of electrons F passes between the 50 electrodes R₁ parallel to the surface of these electrodes, passes through the interval between the electrodes R₁ and the electrodes R₂ at a certain angle different from 90°, then passes between the electrodes R₂. On its approach to the reflecting electrodes P₂ at the outer edges of the electrodes R₂ the bundle is returned to the space between R₂ as shown, again passes between the plates R₁ and is returned by the electrode P₁. The bundle thus advances in zig-zag along the structure in 55 order finally to strike one of the targets C₁ or C₂.

A tension $U \cos \omega t$ is assumed to exist between the pairs of electrodes R₁ and R₂. If the time between the two successive passages through the interval between the electrodes R₁ and R₂ is 60 a half period the electrode will be retarded on each journey if it has been retarded on the first journey. If the form of the electrodes is suitably chosen we then find in consequence of considerations similar to those given for the tube of Fig. 1 that the electrons will be retarded on the average and will consequently supply energy to the oscillatory circuit composed of the tuned transmission line O.

If the form of the reflecting electrode P₁ or P₂

is suitably chosen the electro-static field between the main electrode and the reflecting electrode is such that it forms an electronic lens assisting to maintain the concentration of the electron bundle. This field is represented schematically 5 in Fig. 2 by means of its equipotential lines.

When we produce an oscillator device by the means which have just been described we have at our disposal a negative resistance effect which can be utilised in the amplification of electrical oscillations, for example, of the same order of magnitude as that of the oscillations which can be produced by the tube, when the conditions of operation are adjusted to be outside the range 10 of conditions in which self-oscillation occurs. 15

In the case in which it is desired to employ such tubes as modulated oscillation generators it is possible to provide inside the tubes which have just been described electrodes having an influence 20 on either the intensity or the direction of the electronic bundle or bundles employed.

Other arrangements within the spirit of the invention and within the scope of the appended 25 claims will be apparent to those versed in the art.

What is claimed is :

1. Electron tube arrangement comprising a source of electrons, a high frequency oscillatory circuit comprising co-extensive elongated electrode surfaces, and means for directing the electrons from said source in a sinuous path over 30 said electrode surfaces and in the field thereof for the repeated retardation of the electrons and for the maintenance of oscillations in said oscillatory circuit.

2. Electron tube arrangement comprising a source of electrons, a pair of electrodes each comprising two substantially parallel plates, the respective plates of one of said electrodes lying alongside and coplanar with the respective plates of the other of said electrodes, a high frequency 35 oscillatory circuit connected with said electrodes and means for directing the electrons from said source in a zig-zag path entering the electrodes alternately for the maintenance of oscillations in said oscillatory circuit by the repeated retardation 40 of the electrons.

3. Electron tube arrangement according to claim 2, including electrostatic means at the outer edges of said electrodes for reflecting the electrons entering said electrodes. 50

4. Electron tube arrangement according to claim 2 including converging reflecting electrodes bounding the zig-zag electron path.

5. An electron tube oscillator comprising two pairs of spaced plates with the spaces between the plates in alignment and means associated therewith for setting up a high frequency field between said pairs of plates, means for directing a bundle of electrons between said pairs of plates in succession in zig-zag fashion for the repeated retardation of said electrons by the action of the field between said plates, and means for utilizing the energy derived from the retardation of said electrons for the maintenance of electrical oscillations. 55

6. An electron tube oscillator according to claim 2 wherein said pairs of electrodes are of decreasing width in the direction of travel of said electrons whereby the amplitude of the zig-zag path decreases with the decreasing speed of the 60 electrons. 70
